CLAIM

The ornamental design for a stand for television receiver, as shown and described.

DESCRIPTION

1. Stand for television receiver

1.1 : Perspective

1.2 : Front

1.3 : Back

1.4 : Left

1.5 : Right

1.6 : Top

1.7 : Bottom

1.8 : Reference

The reproduction 1.8 is a reference view showing a state of use of the subject design with a television receiver; the

(Continued)

broken line indicates portions of the article that form no part of the claimed design and a television receiver.
